UNITED STATES PATENT OFFICE.

CHRISTY REGGIO, OF RICHMOND HILL, NEW YORK, ASSIGNOR OF ONE-HALF TO
HENRY C. STOCKMAN, OF ENGLEWOOD, NEW JERSEY.

SHOE AND METHOD OF MAKING SHOES.

Application filed August 18, 1921. Serial No. 493,315.

To all whom it may concern:

Be it known that I, CHRISTY REGGIO, a subject of the King of Italy, and a resident of Richmond Hill, in the county of Queens and the city and State of New York, have ⁵ invented a certain new and useful Improvement in Shoes and Methods of Making Shoes, of which the following is a full, clear, and exact description, reference being had to the accompanying drawings, forming ¹⁰ part of this specification.

This invention relates to improvements in shoes, and methods of making shoes, the soles of which are sewed immediately to the ¹⁵ uppers and which comprise shank-stiffening devices consisting usually of thin strips of steel attached to the inner faces of the soles.

The main object of the invention is the production of shoes having the shank-stiffening devices within the soles instead ²⁰ of on their inner faces, and so made as to render it feasible to practice the invention in manufacturing shoes of high grades.

The invention consists of a shoe and a ²⁵ method of making shoes, the shoe having the novel sole which is herein described and defined in the claims, and having a shank-stiffening device enveloped by parts of the sole, and having in the stitching which ³⁰ connects the sole with the upper two forms of stitching, and the method of making shoes being that which is particularly set forth and claimed herein.

On the accompanying three sheets of ³⁵ drawings, on which like reference-numerals designate like parts in different views:

Fig. 1 illustrates a shoe made by this method and comprising the above-mentioned novel sole, enveloped shank-stiffening device ⁴⁰ and two forms of stitching which connect the sole with the upper;

Fig. 2 is a face view of a piece of sole leather having the shape of a sole;

Fig. 3, an enlarged top face view of the ⁴⁵ same piece, in the ball of which a channel has been cut;

Fig. 4, a longitudinal section of this piece, it having been split from the rear end to the ball;

Fig. 5, a bottom face view of a fragment ⁵⁰ thereof which forms its shank portion;

Fig. 6, an edge view of the rear portion including the shank and a small fragment of the ball;

Fig. 7, an edge view of the same rear portion, the breast for the heel having been cut; ⁵⁵

Fig. 8, a fragmental view of the sole and upper lasted and partly sewed together wrong side out;

Fig. 9, a fragmental view of the sole ⁶⁰ and upper partly lasted right side out, this view showing also the shank-stiffening device;

Fig. 10, a view of the parts shown in Fig. 9, at a later stage of the work; ⁶⁵

Fig. 11, a cross-section on plane 11—11, Fig. 10, of the last and portions of the partly made shoe;

Fig. 12, a fragmental longitudinal section on the plane 12—12, Fig. 9, of the last and ⁷⁰ partly made shoe;

Fig. 13, a fragmental cross-section on plane 13—13, Fig. 8, of the last, sole and upper; and

Fig. 14, a bottom view of a nearly finished ⁷⁵ shoe.

This invention may be practiced in the manufacture of shoes for persons of both sexes and all ages. Although a shoe such as women commonly wear is shown, it will ⁸⁰ be evident to a shoemaker or shoe manufacturer that men's children's and infants' shoes can also be made by following the method herein described. It will also be evident to him that men's or women's or ⁸⁵ children's or infants' shoes of many different forms and styles can be so made.

Some of the known shoes which comprise soles sewed immediately to the uppers and have shank-stiffening devices are what are ⁹⁰ called turnshoes, and others are what are called McKay shoes, the upper and sole of a turnshoe being lasted and sewed together wrong side out and then turned right side out, and the upper and sole of a McKay ⁹⁵ shoe being lasted and sewed together right side out, the sewing being done with a McKay sewing machine after the last has been removed. A turnshoe is generally believed to be better than a McKay shoe ¹⁰⁰ when both are made of stock of the same quality, for the sole of the turnshoe is not

perforated as is that of a McKay shoe and the stitching of the turnshoe is better protected than McKay stitching can be.

The shank-stiffening devices of such shoes sometimes work loose, or wear away their fastenings, at the front ends of the strips of stiffening material, and then they render the shoes uncomfortable by pressing and rubbing against the feet.

10 These well known facts concerning shoes of the two classes above indicated have been utilized in producing this invention, as will be made clear by the following description.

15 The upper 15 (Fig. 1) of this shoe is like that of a common turnshoe, and the leather of the sole is shaped by trimming it as soles are usually trimmed, to fit it to the last. The shaped sole 16 (Fig. 2) is then channeled in the inner face 17 of its front 20 portion, split from its rear end to the ball, cut through its outer face to provide cover for stitching at the sides of the shank, and "breasted." These operations may be performed either in the preferred order in 25 which they are here mentioned or in a different order. The channel 18 (Figs. 3 and 4) in the front portion and inner face of the sole is like the channel in the sole of a common turnshoe, except that the latter 30 extends throughout the length of the sole whereas channel 18, which extends along the sides and front of the ball 19, does not extend backward from the ball. The rear portion of the sole is split midway, or 35 thereabouts, between its faces so that it is divided into the two sections 20 and 21, the outer surfaces of which are respectively portions of the top or inner surface 17 and of the bottom 22 of the sole. When the outer 40 face or bottom of the sole is cut to provide cover for the stitching, as aforesaid, the covers 23 and 24 are formed. They are at the sides of the shank only and are like those parts of the sole of a McKay-sewed 45 shoe which cover the stitching at the bottom of the sole. The sole is breasted, i. e., cut so that a thin facing 25 is provided for the front of the heel, in a well known way.

50 The method which forms part of this invention is particularly illustrated in Figs. 8 et seq. to 14 inclusive. In the practice of it the above-described sole, channeled, split externally grooved, and breasted, is utilized together with an ordinary upper.

55 The sole and upper are first lasted, the inner face 17 of the sole and the lining 26 of the upper being outward, and then the ball 19 and front portions of the upper are sewed together, the stitching 27 being partly within the channel 18 and passing through that portion of the sole which is between its edge and the channel and thence through the material of the upper from its outer surface. This part of the method is illustrated 60 in Figs. 8 and 13 and is the same as that

part of the method of making a turnshoe which consists in and concerns the sewing of the front portion of the upper to the ball of the sole.

Then the last 28 (Fig. 13) is removed, the sole and upper are turned right side out, and the counter 29 is inserted between the lining 26 and the outer part of the upper.

Next, the sole and upper containing the counter are put on another last, the mate 75 of that first used (see Fig. 9), and between this last 30 and section 20 of the sole is placed a thin nail-clinching plate 31 (Figs. 11 and 12) of steel. The section 21 of the sole is not shown in Fig. 9 or Fig. 10. It is kept out of the way when work about to be described is being done, by turning it over against the ball of the sole and temporarily fastening it there.

On the bottom of the section 20, where the heel is to be affixed to the sole, is laid a piece 32 of leather and this is there tacked to that section.

The shank-stiffening device 33 is laid on and attached to that section of the sole. 90 This device is a short strip of steel and may include the longitudinal rib 34 or may be flat or but slightly curved in cross-section. It has prongs 35 at its ends and is attached to section 20 by driving the prongs through 95 it and against the plate 31 and thus clinching them on the inner face of the sole (Figs. 9 and 12.)

When this has been done parts of the material comprising the rear portion of the upper and the counter are drawn over the section 20 and tacked to it, as indicated by Fig. 10, and afterwards the outer section 21 of the sole is turned back and laid on the shank-stiffening device and on the over-turned parts of the upper.

Next, the last 30 and plate 31 are removed, and then the sole and upper are sewed together at the sides of the shank, where the stitching passes from the inner face of section 20 through that section and thence through the overlapping material of the upper and thence through those portions of the outer section 21 of the sole on the under sides of which are the covers 23 and 24. 110 This stitching may be done with a McKay sewing machine, or by hand. It is expected that it will be done with such a machine, by manufacturers of shoes who may practice 115 this method.

The rest of the work, or that required to finish the shoe after what has been described above has been done, is such as workmen making shoes usually do after the sole and upper of a shoe have been sewed together.

120 It will be perceived that a shoe having the characteristics of that which is herein described and claimed is a peculiar turnshoe, the portion in front of the shank being the same as the corresponding portion of a com- 125

mon turnshoe, while the shank is similar in some particulars to and different in others from that of a McKay shoe.

Although the sewing described consists of two forms long known in the art, yet a common turnshoe, does not have a sole divided into sections as is the above-described sole, and does not have a shank-stiffening device enveloped by parts of the sole and held in place both by fastenings which penetrate the sole and by the stitching at the sides of the shank. Since the shank of a shoe does not get as much hard wear as does the ball, the stitching at the shank of this shoe is likely to last until the shoe is worn out or in need of a new sole, so that the sole of the shoe and the stitching which unites it to the upper are in effect as durable, it is believed, as are the corresponding parts of a common turnshoe.

Having described my invention, I claim:

1. A shoe comprising the herein defined sole, and a shank-stiffening device, the sole being a single piece of stock and being split behind the ball into two sections, these being an outer section and an inner section, and the ball having in it a channel such as is commonly made in the sole of a turn-shoe, the stiffening-device being between said sections and attached to the inner section, the front portion of the upper being sewed to the solid ball of the sole, the stitches passing from the channel through the stock which is between it and the edge of the sole and thence through the upper from the exterior

to the interior thereof, and other portions of the upper extending between and being sewed to both of said sections at the sides of the shank.

2. The herein defined method of making a shoe comprising an ordinary upper, a shank-stiffening device, and a sole consisting of a single piece of stock split behind the ball into two sections, these being an outer section and an inner section, and the ball having in it a channel such as is commonly made in the sole of a turn-shoe, the method consisting in first lasting the sole and upper inside out, then sewing the front portions of the upper and ball of the sole together as the sole and upper of a turnshoe are commonly sewed together, then removing the last, then turning the upper and sole, then putting them right side out on a last after the counter has been inserted in the upper, then drawing portions of the upper and counter over the edges of the inner section of the sole and nailing those portions to that section and laying the shank-stiffening device on and fastening it to that section, then placing the outer section of the sole over the inner section, shank-stiffening device and nailed portions of the upper and counter and removing the last, then sewing together said sections and those portions of the upper which extend between them, from the ball to the heel-seat, and then finishing the shoe as a shoe is commonly finished after the upper and sole have been sewed together.

CHRISTY REGGIO.
